UNITED STATES PATENT OFFICE.

CHARLES A. BLANK, OF MILLER, INDIANA, ASSIGNOR OF ONE-HALF TO ARTHUR M. BLANK, OF MILLER, INDIANA.

VENDING-MACHINE.

1,267,965.

Specification of Letters Patent. Patented May 28, 1918.

Application filed December 16, 1915. Serial No. 67,810.

To all whom it may concern:

Be it known that I, CHARLES A. BLANK, a citizen of the United States, residing at Miller, in the county of Lake and State of Indiana, have invented certain new and useful Improvements in Vending-Machines, of which the following is a specification.

My invention relates to an improvement in vending machines and appertains more particularly to that type of machine in which the coin or check used acts as a connector and causes an otherwise freely movable handle to be engaged with tripping means for the delivery of the goods.

The objects of my invention are to produce a machine of this type in which the goods are kept in alinement upon shelves, the coins or connectors are exhibited to public view for the prevention of the use of slugs; the provision of means for separating the coins which are good from those which are bad.

I further propose to provide an apparatus in which the removal of all the articles from a shelf is made known to the proprietor of the machine by a signal and is made known to the vendee by the closing of the coin slot of the particular section which is exhausted.

I further provide means whereby the dispensing device is held out of its normal position until the handle operating it is returned to its normal position. Further objects and advantages of my invention will become apparent and will be pointed out in the specification and claims.

In the accompanying drawings:—

Figure 1 is a view of the unit seen from the operating side;

Fig. 2 is a view from the front of a unit with the door partly broken away;

Figs. 3 and 4 are transverse vertical sections taken on lines 3—3 and 4—4 of Fig. 1;

Fig. 5 is a horizontal section taken above one of the shelves;

Fig. 6 is an enlarged vertical longitudinal section, through two of the shelves at the receiving end of the machine;

Figs. 7 and 8 are fragmentary perspective views showing the tripping mechanism in its normal and working positions;

Fig. 9 is an enlarged side elevation of the coin-controlled mechanism;

Fig. 10 is a horizontal section taken on line 10—10 of Fig. 9;

Fig. 11 is a transverse vertical section

taken on line 11—11 of Fig. 9, showing the interior of the coin-controlled mechanism; and

Fig. 12 is an enlarged side elevation of the coin-controlled mechanism showing a modified form of the coin-deflector.

The frame A is provided with front walls B and C, and a number of slanting shelves 1, which are the supports or trays which hold the goods D to be vended.

At the lower end of the shelves 1 is pivoted at 2 a flat section of metal or wood 3, carrying side members 4 and 5 which in turn support two metal plates 6 and 7. The distance between plates 6 and 7 is sufficient to contain one of the cylinders of goods D.

In the normal position of the section 3, members 4 and 5 and plates 6 and 7 herein-after spoken of as the dispensing means, there is sufficient room between the shelf 1 and the lower edge of the plate 7 to permit the passage of one of the cylinders D. In the middle of section 3 is provided a slot 8 which is engaged by a guide 9 fastened to the bottom of the shelves 1.

To the upper edges of the shelves 1 are pivoted two longitudinal strips 10 and 11 which carry the beveled and flanged plates 12 and 13. The beveled portions of these plates are held together by means of a spring 14. The parts 10, 11, 12, 13 and 14 are hereinafter spoken of as the alining means.

I may also provide bearing plates 15 and 16, which are engaged by the beveled portions of the plates 12 and 13. On the bottom of the section 3 is an upright flanged plate 18. On the other side of section 3 is provided a bearing plate 19. On the side of the shelves 1 is a gravity catch 20 supported by a base 21. Coil springs 22 and 23 are provided to hold the dispensing means normally in a position for operation.

I will now describe the operation of the parts already explained.

The goods, preferably in the form of cylinders D, are placed upon the shelves 1. Upon the operation of the handle, which will be described later, the upright flanged plate 18 is forced downward carrying section 3 with it. Section 3 is carried about the hinge 2 in an arc of a circle, and when brought to the limit of movement the gravity catch 20 engages the bearing plate 19 for the purpose of holding the section 3 out of its normal position. The plate 6 will be

dropped from in front of the cylinders or goods D, and one of the cylinders will thus be permitted to roll off the end of the shelf 1.

The plate 7 will be dropped down in front 5 of the remaining cylinders so as not to permit the release of more than one cylinder at each operation. At the same time the flanged and beveled plates 12 and 13 will have been forced apart at the bottom against 10 the action of the spring 14, causing the longitudinal strips 10 and 11 to impinge against the ends of the cylinders D for the purpose of straightening them up and keeping them in an aligned position.

15 Upon the return movement of the operating handle the gravity catch 20 is released, thus permitting the dispensing means to be returned by the springs 22 and 23 to its normal closed position. The spring 14 will pull 20 the two beveled portions of the plates 12 and 13 toward each other, thus returning the alining means to its normal position. Upon the lowering of the plate 6, out of the path of the cylinders D so as to permit one 25 cylinder D to be rolled off the end, the plate 7 will descend into engagement with the shelf 1, to preclude the passage of any further cylinders of goods D.

Upon the release of the section 3, the plate 30 7 will be removed from its engagement with the shelf 1, and plate 6 will be returned to its normal position, and one cylinder of goods D will be permitted to roll down to the end of the shelf 1, and be stopped by plate 6.

A chute 24 leads to a small cup for the return of bad coins or slugs, or to a receptacle on the interior of the machine for their collection. Each shelf 1, in a unit, and I 40 preferably provide six shelves, is given a chute such as 25 controlling the operation of that separate shelf. This chute 25 mounted upon wall B, has a bulge 26 and a slot 26^a, so that a coin in dropping into the chute 25 45 will be forced outward by the bulge 26 into the slot 26^a in a position to be engaged by the tripping means. Beside the bottom of the chute 25 is located a deflector 27 pivoted at 28 on wall B.

50 One end of this deflector 27 has a flange 29, which is adapted to be placed in the path of the coins in chute 25. At the other end of the deflector 27 is placed a coil spring 30, which connects the deflector with a bell 55 crank lever 31 pivoted at 32 on wall B. This lever 31 is engaged with and operated by a stud 33 located on the plate 5 of the dispensing means.

This lever 31 is normally in a raised position and is held there by means of spring 34. The flange 29 on the deflector 27 is normally out of the path of the coin and is held so by means of a straight spring 35. A modification of the deflector 27 is shown in 65 Fig. 12, in which the deflector 27 is in the

form of a tube normally directed at and opening in the chute 24, so that bad coins may be passed thereinto, the tube directing the coins in to the chute 36' for the passage of good ones.

In the front of the machine is provided a series of coin chutes 36, one for each shelf, these chutes 36, have one side cut away so that the coin is visible in its passage therethrough. Each of the coin chutes 36 has a sharp bend 37. I may also provide an orifice 38 for the removal of slugs if desired. These chutes 36 open into a coin chute 39, which leads to a common receptacle, not shown, for all the coins traveling from the exhibiting chutes 36. These chutes 36 are supported between walls B and C and are for the purpose of exhibiting all but a small portion of the coin, thus disclosing any attempt to use a slug or like device.

70 The chutes 36 are so arranged that each coin kicks the coin which precedes it into the chute 39. The chutes 36 are joined to the chutes 25 at an angle and are adapted to receive the coins which the flange 29 on 75 the deflector 27 gets in the way of to prevent their passage into the chute 24. At 40 on the rear of the machine lever 41 is pivoted. This lever 41 extends the entire length of the machine and an end of the lever protrudes through the slot 42 in the face of the machine. Spring 42' is connected to the lever 41 and the frame A for the purpose of holding the lever 41 at the top of the slot 42.

80 This lever 41 carries tripping lever 43 which is provided with projections 44 and 45, which extend beyond lever 41 at both edges thereof. A bolt 46 extends through the projections 44 and 45 and lever 41, to form a pivot for the lever 43. At the other 90 end of the projections a cross strip 47 is affixed in close proximity to the chute 25 and slot 26^a. At the other end of the tripping lever 43 a stud 48 is rigidly attached which passes laterally through the lever 41. 100 The free end of the stud 48 is provided with a head 49.

110 The tripping lever 43 is forced out from the lever 41 by means of a spring 50, whereby one end of the tripping lever 43 is normally forced away from the lever 41.

A block 51 having a countersink 52 is attached to the side of lever 41 and the stud 48 will protrude through a suitable orifice in the block 51, and the head 49 of the stud 120 48 will be received in the countersink 52.

A cross piece 53 carrying a light bar 54 is pivoted on the lower side of each shelf 1. To the side of the cross bar is attached a lever 55, the opposite ends of which are punctured as at 56 and 57 and are adapted to receive wires 58 and 59 therein. The wire 58 is connected to either a mechanical or electrical signal of some sort, not shown, for the purpose of warning the proprietor or 130

owner of the machine that the goods on the shelf are exhausted. The wire 59 is connected to a bell-crank-lever 60 so located that one end of the lever can close the coin slot 61, the bell crank lever being normally held in a position away from the slot 61 by means of a flat spring 62. At the bottom of the space between the walls B and C, I provide a slanting surface 63 which is 10 padded so as to break the fall of the cylinders D, which upon striking it roll under the front wall 64 and into the box 65 from whence they can be readily taken, as they roll off the shelves.

15 The front of each unit is covered by a glass door so that the cylinders D and coin exhibiting chute 36 may be plainly seen. I also provide reinforcing bars 66 within the door for the purpose of protecting the glass 20 from possible contact with the cylinders D in their fall.

Upon the insertion of the coin into my machine it drops down into the chute 25 and strikes the bulge 26 which forces it out 25 against the cross piece 47 on the trip lever 43. Upon the pushing down of the lever 41 in the slot 42 the coin will be frictionally engaged by the cross piece 47 and as the lever is depressed the coin mounting upon 30 the bulge 26 in the chute 25 will protrude through the slot 26^a and will force the cross strip 47 away from the chute 25, which will cause the tripping lever 43 to oscillate about the pivot 46 against the action of the spring 35 50. The stud 48 will be forced laterally through the lever 41, and block 51 causing the head 49 of the stud 48 to protrude beyond the countersink 52 and come into engagement with the upright flange 18 attached to the dispensing means, which will 40 be caused to operate as previously set forth.

Upon the depression of the dispensing means, the bell crank lever 31 and the deflector 27 will be pushed over so that when the 45 coin is forced past the bulge 26 by the cross strip 47, it will be permitted to drop by gravity, if a good coin, and will be deflected into the chute 36. If however, the coin is small or otherwise incapable of operating 50 the machine, the cross strip 47 will be forced but a little way in or away from the chute 25 when the coin will have reached the end of the bulge 26, and the coin will by gravity drop down the chute 24, as the deflector will 55 not be operated unless and until the dispensing means is appreciably depressed.

It is apparent that there are many opportunities for a departure from the exact description herein set forth. For instance, 60 instead of having the coin chute 36 lead into a common chute 39, I may provide an individual collector for each shelf. Or I may have all of the coins pass immediately into a compartment beneath in which an operator might investigate the coins used. The

operator might be placed so as to manually control the operation of the levers for the dropping of the cylinders from the shelf.

It is, of course, obvious that I may use any sort of slug protectors or preventers 70 such as magnets, etc., in the chute 25 in addition to the protection already set forth, hence I do not wish to limit myself to the invention as set forth in the specification and drawings, but—

I claim:

1. In a vending machine, a shelf having pivotally mounted sides, actuated means connected thereto, and actuating means for positively engaging said actuated means for 80 alining the goods upon the shelf.

2. In a vending machine, the combination with a frame, of a shelf, strips pivotally mounted upon said shelf, and actuating means, in engagement with the said actuated 85 means for oscillating the strips about their pivots for the purpose of alining goods upon said shelf.

3. In a vending machine, the combination with a frame, of a shelf, longitudinal strips 90 pivoted thereon, beveled actuated means mounted on said strips, dispensing means mounted upon said shelf in engagement with said beveled actuated means, means for operating said dispensing means, the whole being 95 so arranged that upon the operation of the dispensing means the longitudinal strips will be oscillated about their pivots on the shelf for the purpose of alining goods upon said shelf.

4. In a vending machine, the combination with a frame, of a shelf having movable sides, dispensing means pivotally mounted thereon, actuated means connected to the movable sides of said shelf in engagement 105 with the dispensing means, and means for actuating said dispensing means so that the sides of said shelf will be positively moved together for the purpose of alining goods upon said shelf.

5. In a vending machine, the combination with a frame, of a shelf, having automatically movable sides, a guide mounted on said shelf, dispensing means pivotally mounted upon said shelf having a slot, said 115 guide adapted to pass through the slot in said dispensing means, and means for operating the movable sides of said shelf and said dispensing means upon said guide, whereby a specified amount of goods is released at each operation, and goods are 120 alined upon the shelf.

6. In a vending machine, the combination with a frame, of a shelf, a gravity catch mounted on said shelf, and actuating means 125 capable of engaging with and operating said dispensing means, said gravity catch being adapted to hold the dispensing means out of its normal position until the disengagement of the operating means therewith.

130

7. In a vending machine, the combination with a frame, of a shelf, a gravity catch mounted on said shelf, and actuating means capable of engaging with and operating said dispensing means, said gravity catch being adapted to hold the dispensing means out of its normal position until the disengage-

ment of the operating means therewith, said operating means being adapted to release the dispensing means from the gravity catch 10 after said disengagement.

In testimony whereof I affix my signature.

CHARLES A. BLANK.

Copies of this patent may be obtained for five cents each, by addressing the "Commissioner of Patents, Washington, D. C."
